UNITED STATES PATENT OFFICE

JOSEPH M. LUCARELLE, OF BRIDGEPORT, CONNECTICUT, ASSIGNOR TO DICTAPHONE CORPORATION, OF BRIDGEPORT, CONNECTICUT, A CORPORATION OF NEW YORK

CORRECTION DEVICE

Application filed March 2, 1927. Serial No. 172,037.

This invention relates to improvements in correction devices for dictating machines, and more particularly to such machines employed in connection with the transcribing of dictation into typewritten form.

In connection with machines of this character, it has been usual to employ a memorandum sheet having printed thereon a scale corresponding to a scale on the dictating machine upon which sheet the dictator may note certain instructions and corrections, this memorandum sheet being turned over to the transcriber as a guide in transcribing the record. In making notations on this memorandum sheet, it has been necessary for the dictator to first note the position of the pointer on the scale of the dictating machine, then locate the corresponding indication on the scale of the memorandum sheet, and then make proper notations on such memorandum sheet. In doing this, error is liable to occur since the dictator is required to make two separate readings from two separate places, thereby naturally increasing the possibility of error.

According to the present invention, the necessity of making two separate readings is eliminated, and this is accomplished by making it unnecessary for the dictator to read either scale.

Many means and ways have been proposed to serve as correction means for dictating machines, and one of such means was to provide a narrow stand for holding a writing tablet very close and in front of the revolving wax cylinder. Such a method has proven to be disadvantageous due to the very limited amount of space for notation purposes as well as being so close to the revolving wax cylinder that the marking pencil might accidentally be brought against the cylinder, unless the dictator is extremely careful.

An object of the invention is to provide a large and conveniently located memorandum device with means for permitting the dictator to give the transcriber instructions regarding the work, without the mental effort and careful attention heretofore found necessary.

A feature of the invention is the provision of means which permits any necessary ad-

justments to be easily made so that the correction device will always be accurate.

Other objects and advantages will hereinafter appear.

The means at present preferred for accomplishing these results are shown in the accompanying drawings, in which—

Figure 1 is a perspective view of a memorandum device in accordance with the present invention, showing but a portion of a dictating machine.

Fig. 2 is a rear elevation of a dictating machine showing the present invention applied thereto.

Fig. 3 is an end view of the device shown in Figs. 1 and 2.

Fig. 4 is a vertical section taken through the indicator of the present invention on line 4—4 of Fig. 3.

As shown in the accompanying drawings, the dictating machine 10 comprises a base 11 below which is a motor box 12 containing mechanism (not shown) for imparting rotation to the mandrel 13 which holds a record-blank (not shown) and for moving the sound-box carriage 14 longitudinally of said mandrel.

Rising from the base is a pair of standards 15 between which extends back-space bar 17 and also a guide tube 18 along which the carriage travels axially of the mandrel upon suitable operations of a control lever 19. The carriage is prevented from rotating on said tube by means of a stabilizer arm 20 which straddles a rod 21 extending between said standards 15. The carriage may be freely moved by hand along said tube and rod 21 when the lever 19 is set in its neutral position shown in Fig. 3. The standards 15 have forwardly projecting arms 16 carrying a scale 22 which extends across the machine to cooperate with a pointer or indicator 23 mounted on the carriage.

The mechanism above described, namely the dictating machine per se and the indicator pad shelf 32, are now well known in the art and consequently need no further detail description. Suffice it to say that the pad 32 is made sufficiently large to take not only marks or abbreviated memoranda but also 101

detail instructions when the dictator feels that this is necessary or desirable. In use, this form of memorandum device has proven extremely advantageous for the above reasons, but it has had the disadvantage that it was necessary for the dictator to first note by reference to the scale 22 and pointer 23 on the carriage the position of the carriage with reference to the scale and carry that note mentally until the same place on the scale 36 of the indicator pad 35 is found, and then to make a mark at that place on the indicator scale 36, all the while, of course, remembering what it was that he desired to communicate to the transcriber by the notation.

This disadvantage is obviated by the present invention by the provision of means on the relatively large scale pad 35 for indicating thereon the position of the carriage relative to the record and/or scale 22 without requiring any mental effort on the part of the dictator, yet the location and size of the indicator pad 35 is not changed, so that the advantages above referred to have been retained.

This is accomplished by the present invention by the provision of an indicator 37 which is mounted on the shelf 32 or some adjacent part so as to move longitudinally of the scale 36 on the scale pad 35. In the form of the present invention herein shown, the indicator 37 has upwardly extending ears 38 provided with slots 39 for receiving a guide rod 40 having its ends supported in brackets 41 and 42 carried by the shelf 32 and thus the indicator 37 may slide on the pad 35 guided by the rod 40.

For the purpose of moving the indicator 37 co-ordinately and simultaneously with the sound-box carriage 14, the indicator 37 has provided between its upstanding ears 38 a member 43 having apertured ears 44 through which the guide rod 40 extends and a protruding arm 45 to which a transmission cord 46 is connected. The member 43 fits snugly between the upstanding ears 38 of the indicator 37, so as to accurately control the movement of the indicator, yet there is sufficient freedom to permit the indicator to move vertically by reason of the slot 39 so as to engage by its own weight the top surface of the pad regardless of the reducing thickness thereof caused by the consumption of the pad sheet by sheet. The freedom between the indicator 37 and the member 43 is also sufficient to permit the indicator 37 to be tilted upwardly away from operative position in the direction of the arrow shown in Fig. 4 by manipulation of a finger-piece 47 on one of the ears 38 so as to permit a new pad to be inserted between the indicator and the shelf 32.

Of course, the indicator 37 may be caused to traverse the scales 36 of the pad 35 by any suitable transmission or other movement imparting device connected to the sound-box

carriage 14. However, as above stated, it is at present found preferable to utilize a transmission cord 46 for this purpose. This transmission cord 46 is preferably continuous, and after being led over suitable guiding means, hereinafter referred to in detail, has its end connected to a link 48. This link 48 is firmly secured to the sound-box carriage 14 by means hereinafter described. From the link 48, one stretch of the cord 46 extends over a pulley 49 carried on the back-space bar 17, then over a pulley 50 at the other side of the machine, then downwardly to a pulley 51 mounted in the bracket 42 carried by the shelf 34, then over the pulley 51 and downwardly and forwardly to a pulley 52 carried by the bracket 41 at the forward end of the shelf 32, then backwardly and upwardly over a pulley 53 also carried by the bracket 42, then upwardly over a pulley 54 and from the pulley 54 back to the link 48. With this arrangement, when the sound-box carriage 14 moves from left to right, as it usually does in making a record, the indicator 37 will be moved from the back toward the front of the machine along the scale pad 35. Since there are no motion-reducing or increasing devices in the transmission, the movement of the indicator 37 will be the same relatively to the scale pad as the movement of the sound-box carriage 14 is with respect to the record.

In order to maintain the transmission cord taut to accommodate for slackening or tightening thereof due to atmospheric changes or extensive use, and also to permit the base 11 to be swung relative to the motor box 12 on its hinge 55 without breaking or straining the transmission cord 46, the pulleys 50 and 54 are mounted in an arm 56 pivoted on a screw 57 mounted in the back-space bar 17. The arm 56 has an upstanding ear 58 connected to a spring 59 whose other end is connected to an arm 60 which is supported upon the back space bar in any desired manner. Hence the tendency is for the end of the arm 56 which carries the pulleys 50 and 54 to swing upwardly and this takes up slack and yields under tension, thereby holding the transmission cord 46 taut under all conditions.

Since the marked sheet of the indication pad 35 is to be used in connection with another machine such as a transcribing machine which may have a similar indicator or merely a scale and pointer, it is customary that the transcribing machine and dictating machine both have their scales coordinated. That is to say, when the scales are so arranged that a record is taken from one machine and put on another, a particular point on the record is indicated by the same number on the scale of the second machine that it was indicated by on the scale of the first machine when the record was on the first machine. Hence, it is extremely important that the indicator 37

be coordinated with the scale 22 and point 23 of the machine. For this purpose, the link 48 is not permanently and unalterably secured to the sound-box carriage 14, but is merely clamped thereto in any suitable manner, as by the flat headed screw 61, which passes through a slot 62 formed in said link and extending longitudinally thereof. When it is desired to adjust the indicator 37 with regard to the scale pad and with respect of the scale 22 and pointer 23, the screw 61 is loosened and the indicator 37 is moved to a position on the scale 36 which accurately corresponds with the position of the pointer 23 on the scale 22. Then, without further adjustment, the screw 61 is tightened to firmly lock the link 48 to the carriage 14.

Other forms of adjusting or coordinating mechanisms may, of course, be provided within the scope of this invention.

It should be noted that the indicator 37 does not actually provide a surface against which a pencil is held to make a mark, but instead is merely provided with arrows 63 which indicate the position on the scales 36 which should be marked by a pencil. The indicator 37 is made unsuitable for pencil guiding purposes, because it has been found that when a pencil is brought against the surface of the indicator 37 the position of the latter might be shifted substantially due to the pressure of the pencil thereagainst and hence the indication would not be at the proper place.

Variations and modifications may be made within the scope of this invention and portions of the improvements may be used without others.

Having now described the invention, what is claimed as new and for which it is desired to obtain Letters-Patent, is:—

1. In an indicator device for dictation machines, comprising a movable sound-box; a support for an indication scale pad located at one side of the machine at a point remote from the sound-box; and an indicator movable over said pad; and means for moving the indicator coordinately with the sound-box.

2. In an indicator device for dictation machines, comprising a movable sound-box; a support for an indication scale pad located at one side of the machine at a point remote from the sound-box; a guide carried by said support; an indicator slidably mounted on said guide; and means for moving said indicator coordinately with the sound-box of said machine; and means for permitting the indicator to follow the surface of the uppermost sheet of the scale pad regardless of the changing thickness of said scale pad as sheet by sheet of the pad is used.

3. In an indicator device for dictation machines, a frame and a sound-box movable over a record; a pointer carried by said sound-box and adapted to indicate the relative position

of the sound-box with relation to the record; a support for an indicator scale pad located at one side of the machine at a point remote from said sound-box; a guide carried on said support and an indicator slidably carried by said guide and movable coordinately with the sound-box; and a cord transmission device carried by the frame, said transmission means being connected to the sound-box and indicator, thereby causing said indicator to move along the scale when the sound-box travels.

4. In an indicator device for dictation machines, a frame; a sound-box movable over a record; a pointer carried by said sound-box and adapted to indicate the relative position of the sound-box with relation to the record; a support for an indicator scale pad located at one side of the machine at a point remote from said sound-box; a guide carried on said support; an indicator slidably carried by said guide and movable with the sound-box; transmission means carried by the frame, said transmission means being connected to the sound-box and indicator; and means for adjusting the relation of the sound-box to the indicator which is carried by the guide along the scale pad, so that the indicator will correspond with the scale pad in the same manner that the pointer carried by the sound-box corresponds with the record.

5. In an indicator device for dictation machines, a frame; a sound-box movable over a record; a pointer carried by said sound-box and adapted to indicate the position of the sound-box with relation of the record; a support for an indicator scale pad located at one side of the machine at a point remote from said sound-box; a guide carried on said support and an indicator slidably carried by said guide and movable with the sound-box; a flexible transmission means supported on the frame, said transmission means being connected to the sound-box and indicator; means for holding the cord of the transmission means taut; and means for adjusting the relation of the sound-box to the indicator which is carried by the guide along the scale pad so that the indicator will correspond with the scale pad in the same manner that the pointer carried by the sound-box corresponds with the record.

6. In an indicator device for dictation machines, a frame; a sound-box movable over a record; a support for an indicator scale pad located at one side of said machine at a point remote from said sound-box; a guide carried on said support; an indicator slidably carried by said guide and movable simultaneously with the sound-box; a flexible transmission means carried by the frame, said transmission means being connected to the sound-box and indicator; means for holding the cord of the transmission means taut; and means for adjusting the connection of the indicator

and sound-box to the transmission means to render coordinate the movement of the sound-box relative to the record and the movement of the indicator relative to the scale pad support.

- 5 7. In an indicator device for dictation machines, comprising an indicator carried by a movable sound-box; a support for an indication scale pad located at one side of the machine at a point remote from the sound-box; a guide rod carried by said support; a second indicator, said second indicator being movable coordinately with the sound-box and over said pad on the guide; and means for 10 moving the second indicator simultaneously with and proportionately to the relative movement of the first-named indicator.

8. In an indicator device for dictation machines, a frame; a sound-box movable over a record; a pointer carried by said sound-box and adapted to indicate the positions of the sound-box with relation to the record; a support for an indicator scale pad located at one side of the machine at a point remote from 20 said sound-box; a guide carried on said support; an indicator slidably carried by said guide and movable coordinately with the sound-box; a cord transmission device carried by the frame, said transmission means being 25 connected to the sound-box and indicator, thereby causing said indicator to move along the scale when the sound-box travels; and means for permitting the indicator to follow the surface of the uppermost sheet of the 30 scale pad regardless of the changing thickness of said scale pad as sheet by sheet of the pad is used.

9. In an indicator device for dictation machines, a frame; a sound-box movable over a record; a pointer carried by said sound-box and adapted to indicate the relative position 40 of the sound-box with relation to the record; a support for an indicator scale pad located at one side of the machine at a point remote from said sound-box; a guide carried on said support; an indicator slidably carried by said guide and movable with the sound-box; transmission means carried by the frame, said transmission means being connected to the 45 sound-box and indicator; means for adjusting the relation of the sound-box to the indicator which is carried by the guide along the scale pad so that the indicator will correspond with the scale pad in the same manner that the pointer carried by the sound-box corresponds with the record; and means for permitting the indicator to follow the surface of the uppermost sheet of the scale pad regardless of the changing thickness of said 50 scale pad as sheet by sheet of the pad is used.

60 10. In an indicator device for dictation machines, a frame; a sound-box movable over a record; a pointer carried by said sound-box and adapted to indicate the relative position of the sound-box with relation to the record;

a support for an indicator scale pad located at one side of the machine at a point remote from said sound-box; a guide carried on said support and an indicator slidably carried by said guide and movable with the sound-box; a flexible transmission means supported on the frame, said transmission means being connected to the sound-box and indicator; means for holding the cord of the transmission means taut; means for adjusting the relation of the sound-box to the indicator which is carried by the guide along the scale pad so that the indicator will correspond with the scale pad in the same manner that the pointer carried by the sound-box corresponds with the record; and means for permitting the indicator to follow the surface of the uppermost sheet of the scale pad regardless of the changing thickness of said scale pad as sheet by sheet of the pad is used.

85 11. In an indicator device for dictation machines, a frame; a sound-box movable over a record; a support for an indicator scale pad located at one side of said machine remote from said sound-box; a guide carried on said support and an indicator slidably carried by said guide and movable coordinately with the sound-box; a flexible transmission means supported on the frame, said transmission means being connected to the sound-box and indicator; means for holding the cord of the transmission means taut; means for adjusting said indicator carried by the guide along the scale pad so that the indicator will correspond with the relative amount of movement that the sound-box moves over said record; and means for permitting the indicator to follow the surface of the uppermost sheet of the scale pad regardless of the changing thickness of said scale pad as sheet by sheet of the pad is used.

90 12. In an indicator device for dictation machines, comprising an indicator carried by a movable sound-box; a support for an indication scale pad located at one side of the machine at a point remote from the sound-box; a guide carried by said support; a second indicator movable over said pad on the guides coordinately with the sound-box; means for moving the second indicator simultaneously with and proportionately to the relative movement of the first-named indicator; and means for permitting said last-named indicator to follow the surface of the uppermost sheet of the scale pad regardless of the changing thickness of said scale pad as sheet by sheet of the pad is used.

95 13. In an indicator device for dictation machines, comprising a movable sound-box; a support for an indication scale pad located at one side of the machine at a point remote from the sound-box; a guide carried by said support; and an indicator slidably mounted on said guide and movable coordinately with the sound-box of said machine, said indicator being movable in a direction that is sub- 100

stantially at right angles to the direction of the movable sound-box.

14. In an indicator device for dictation machines, comprising a movable sound-box; a support for an indication scale pad located 5 at one side of the machine at a point remote from the sound-box; and an indicator movable over said pad coordinate with the sound-box, said indicator being movable in a direction that is substantially at right angles to the direction of the movable sound-box.

15. In an indicator device for dictation machines, comprising a movable sound-box; a support for an indication scale pad located 10 at one side of the machine at a point remote from the sound-box; a guide carried by said support; an indicator slidably mounted on said guide and movable coordinate with 15 the sound-box of said machine; and means for permitting the indicator to follow the surface of the uppermost sheet of the scale pad regardless of the changing thickness of said scale pad as sheet by sheet of the pad is used, 20 said indicator being movable in a direction that is substantially at right angles to the direction of the movable sound-box.

16. In an indicator device for dictation machines, a frame; a sound-box movable over 25 a record; a pointer carried by said sound-box and adapted to indicate the relative position of the sound-box with relation to the record; a support for an indicator scale pad located at one side of the machine at a point remote 30 from said sound-box; a guide carried on said support and an indicator slidably carried by said guide and movable coordinate with the sound-box; a cord transmission device supported by the frame, said transmission 35 means being connected to the sound-box and indicator, thereby causing said indicator to move along the scale when the sound-box travels; and said indicator being movable in a direction that is substantially at right angles 40 to the direction of the movable sound-box.

17. In an indicator device for dictation machines, a frame; a sound-box movable over a record; a pointer carried by said 45 sound-box and adapted to indicate the relative position of the sound-box with relation to the record; a support for an indicator scale pad located at one side of the machine at a point remote from said sound-box; a guide 50 rod carried on said support and an indicator slidably carried by said guide rod and movable with the soundbox; transmission means carried by the frame, said transmission means being connected to the sound-box 55 and indicator; means for adjusting the relation of the sound-box to the indicator which is carried by the guide along the scale pad so that the indicator will correspond with the scale pad in the same manner that the pointer 60 carried by the sound-box corresponds with

the record; and said indicator being movable in a direction that is substantially at right angles to the direction of the movable sound-box.

18. In an indicator device for dictation 70 machines, a frame; a sound-box movable over a record; a pointer carried by said sound-box and adapted to indicate the relative position of the sound-box with relation to the record; a support for an indicator 75 scale pad located at one side of the machine at a point remote from said sound-box; a guide carried on said support and an indicator slidably carried by said guide and movable with the sound-box; a flexible 80 transmission means carried by the frame, said transmission means being connected to the sound-box and indicator; means for holding the cord of the transmission means taut; and means for adjusting the relation of the 85 sound-box to the indicator which is carried by the guide along the scale pad so that the indicator will correspond with the scale pad in the same manner that the pointer carried by the sound-box corresponds with the record, said indicator being movable in a direction that is substantially at right angles to 90 the direction of the movable sound-box.

19. In an indicator device for dictation 95 machines, a frame; a sound-box movable over a record; a support for an indicator scale pad located at one side of said machine remote from said sound-box; a guide carried on said support and an indicator slidably carried by 100 said guide and movable co-ordinately with the sound-box; a flexible transmission means carried by the frame, said transmission means being connected to the sound-box and indicator; means for holding the cord of the transmission means taut; and means for adjusting said indicator carried by the guide along the scale pad so that the indicator will correspond with the relative amount of movement that the sound-box moves over said record, and said indicator being movable in a 105 direction that is substantially at right angles to the direction of the movable sound-box.

20. In an indicator device for dictation 110 machines, comprising an indicator carried by a movable sound-box; a support for an indication scale pad located at one side of the machine at a point remote from the sound-box; a guide carried by said support; a second indicator, said second indicator movable coordinate with the sound-box and over 115 said pad on the guide; and means for moving the second indicator simultaneously with and proportionately to the relative movement of the first-named indicator, said second indicator being movable in a direction that is 120 substantially at right angles to the direction of the movable sound-box.

21. In an indicator device for dictation 125 machines, a frame; a sound-box movable over a record; a pointer carried by said sound-box 130

- and adapted to indicate the relative position of the sound-box with relation to the record; a support for an indicator scale pad located at one side of the machine at a point remote from said sound-box; a guide carried on said support and an indicator slidably carried by said guide and movable coordinate with the sound-box; a cord transmission device carried by the frame, said transmission means being connected to the sound-box and indicator, thereby causing said indicator to move along the scale when the sound-box travels; and means for permitting the indicator to follow the surface of the uppermost sheet of the scale pad regardless of the changing thickness of said scale pad as sheet by sheet of the pad is used, said indicator being movable in a direction that is substantially at right angles to the direction of the movable sound-box.

- the record; and means for permitting the indicator to follow the surface of the uppermost sheet of the scale pad regardless of the changing thickness of said scale pad as sheet by sheet of the pad is used, and said indicator being movable in a direction that is substantially at right angles to the direction of the movable sound-box.
- 70 75 80 85 90 95 100 105 110 115 120 125 130
22. In an indicator device for dictation machines, a frame; a sound-box movable over a record; a pointer carried by said sound-box and adapted to indicate the relative position of the sound-box with relation to the record; a support for an indicator scale pad located at one side of the machine at a point remote from said sound-box; a guide rod carried on said support and an indicator slidably carried by said guide rod and movable with the sound-box; transmission means carried by the frame, said transmission means being connected to the sound-box and indicator; means for adjusting the relation of the sound-box to the said indicator which is carried by the guide along the scale pad so that the indicator will correspond with the relative amount of movement that the sound-box moves over said record; and means for permitting the indicator to follow the surface of the uppermost sheet of the scale pad regardless of the changing thickness of said scale pad as sheet by sheet of the pad is used, said indicator being movable in a direction that is substantially at right angles to the direction of the movable sound-box.
23. In an indicator device for dictation machines, comprising an indicator carried by a movable sound-box; a support for an indicator scale pad located at one side of the machine at a point remote from the sound-box; a guide rod carried by said support; a second indicator, said second indicator being movable coordinate with the sound-box and over said pad on the guide rod; means for moving the second indicator simultaneously with and proportionately to the relative movement of the first-named indicator; and means for permitting said second indicator to follow in a direction that is substantially at right angles to the direction of the movable sound-box over the surface of the uppermost sheet of the scale pad regardless of the changing thickness of said scale pad as sheet by sheet of the pad is used.
24. In an indicator device for dictation machines, a sound-box movable over a record; a pointer carried by said sound-box and adapted to indicate the relative position of the sound-box to the record; a support for an indicator scale pad located at one side of the machine at a point remote from said sound-box; a guide carried on said support and an indicator slidably carried by said guide and movable with the sound-box; means for adjusting the relation of the sound-box to the indicator which is carried by the guide along the scale pad so that the indicator will correspond with the scale pad in the same manner that the pointer carried by the sound-box corresponds with

that the pointer carried by the sound-box corresponds with the record; said adjustable means comprising a link having an elongated slot therein for the passage of a screw carried by the sound box; and a thumb nut threaded on said screw to hold said link against the sound-box.

27. In an indicator device for dictation machines, a sound-box movable over a record; a pointer carried by said sound-box and adapted to indicate the relative position of the sound-box with the record; a support for an indicator scale pad located at one side of the support and an indicator slidably carried by a guide and movable with the sound-box; said indicator comprising a pair of upwardly extending ears with slots therein for receiving said guide, one of said ears having a finger-piece thereon for manipulation thereof; a member on said guide between said extending ears, said member having a pair of apertured ears receiving said guide rod; and a protruding arm on said member to which a transmission cord is adapted to be connected therewith.

Signed at Bridgeport, in the county of Fairfield, and State of Connecticut, this 1st day of March, 1927.
